(57) **CLAIM**

The ornamental design for a connector housing for electronic apparatus, as shown and described.

DESCRIPTION

FIG. 1 is a front elevation view of the connector housing for electronic apparatus, showing the new design;
FIG. 2 is a rear plan view thereof;
FIG. 3 is a left side elevation view thereof;
FIG. 4 is a right side elevation view thereof;
FIG. 5 is a top plan view thereof;
FIG. 6 is a bottom plan view thereof; and,
FIG. 7 is a front, top plan and right side perspective view thereof.

The broken lines in the drawings illustrate portions of the connector housing for electronic apparatus that form no part of the claimed design.
